UNITED STATES PATENT OFFICE.

WILLIAM P. VROOMAN, OF JOHNSTOWN, NEW YORK, ASSIGNOR TO JOSEPH R. TORREY, OF WORCESTER, MASSACHUSETTS.

COMBINED STOCK AND SAMPLE SHOW-CASE.

SPECIFICATION forming part of Letters Patent No. 331,171, dated November 24, 1885.

Application filed April 24, 1885. Serial No. 163,332. (No model.)

To all whom it may concern:

Be it known that I, WILLIAM P. VROOMAN, a citizen of the United States, residing at Johnstown, in the county of Fulton and State of New York, have invented certain new and useful Improvements in Combined Stock and Sample Show-Cases, of which the following is a specification, reference being had therein to the accompanying drawings.

10 The object of my invention is to provide a show-case of such construction that it is adapted to exhibit samples of cutlery or other small articles to good advantage, while it is at the same time so constructed as to hold 15 a considerable amount of stock of the articles like the samples shown, the stock being conveniently accessible to the salesman without disturbing the samples.

My improved show-case has a glass front 20 and a sliding or hinged door behind, like many other show-cases now in use. I provide the ends and partitions of the case with supports (which are preferably grooves) for trays or shelves, which latter preferably slide easily in 25 or on the supports, so as to be readily removable therefrom. The front ends of the trays or shelves are provided with means for retaining the samples, behind which the stock corresponding to the samples is stored. The 30 purchasers can see the samples through the glass front of the case, and the salesman can readily get at the stock from behind by opening the door without removing the samples from the shelves or trays, and thus the trouble 35 of replacing the samples or danger of losing their tags, if such be attached, is entirely obviated, while a considerable amount of stock advantageously represented by samples and conveniently arranged for ready access may 40 be kept in a comparatively small space.

In the accompanying drawings, Figure 1 is a front view of a show-case embodying my invention. Fig. 2 is a rear view of the same with the door opened. Fig. 3 is a cross-section on line 3 3, Fig. 1, and Fig. 4 is a longitudinal section.

A indicates the bottom of the case, and B the ends thereof, and if the case is to contain more than one series of shelves or trays C one

or more partitions, B', corresponding in shape 50 to the end pieces of the case, will be provided. In the present instance two tiers or series of trays are shown, requiring one partition, B'. The end pieces, B, and the partitions B' are preferably adapted to support the trays or 55 shelves C by being provided with a series of grooves, b, into which the edges of the latter project; but instead of these grooves it is obvious that strips or ribs as b', attached to the end pieces and partitions, may be employed 60 for the same purpose. The front ends of the trays are provided with means for holding the samples in place, preferably by being constructed with compartments formed by small partitions c, to which the samples may be attached by wire loops d, or by spring clips or loops e, or a small holding-rib, as f, at the extreme front end of the tray, will be sufficient 65 to retain the sample in place.

While it is not necessary that the trays or 70 shelves should be removable when the space between them is sufficient to admit of easy access to the stock held thereby, it is deemed preferable that these receptacles for the stock should slide freely in or on their supports, as 75 access to the stock is thereby facilitated; or the trays may be removed altogether the better to exhibit the goods to the purchaser. The stock-receptacles may be simple shelves, or they may be provided with edge projections or ribs, as c', to form trays; or they may 80 be made like ordinary drawers with lips or ledges at their forward ends to hold the samples.

I prefer to make the fronts of my show and 85 stock cases slanting, as shown in the drawings, the better to exhibit the samples and to form trays of different sizes, and thus adapt the lower trays for holding larger articles or more stock than the upper ones; but I do not wish to 90 be understood as limiting my invention to this form of the case. The glass D in the front of the case may be retained in place in the usual or any well-known manner, as by strips a, having overhanging lips, or otherwise.

The back of my case is open, and is closed 95 by a door or doors, as E, which may swing or slide horizontally or vertically.

The glass front of the case is preferably provided with numbers, letters, or other reference-characters corresponding to similar characters on the rear ends of the shelves or trays, so that the latter when removed may always be readily replaced in their proper positions.

When constructed in the manner above described, it is obvious that my case is adapted to hold considerable amount of readily accessible stock in a comparatively small space, and to exhibit samples of the same advantageously. The display-samples need never be handled or soiled; but may remain undisturbed in their compartments until the entire stock is disposed of.

My invention is more particularly for knives and other small articles of cutlery; but may be used for a large variety of other articles.

I am aware that it is not new to provide a show-case having a transparent front with a series of removable stock-exhibiting shelves, and a door behind which closes the rear of the case and permits of access to the said shelves, this construction being shown by Patent No. 242,657, to B. Kohn, and dated June 7, 1881. I do not therefore wish to be understood as claiming the construction above mentioned on which my invention is an improvement.

Having thus described my invention, I claim and desire to secure by Letters Patent—

1. The combination, with a show-case having a transparent front and a door behind, by

which its otherwise open rear portion is closed, of a series of stock-receptacles accessible from behind and provided at their front ends with sample-holding devices, substantially as set forth.

2. The combination, with a show-case having a transparent front and a door behind, by which its otherwise open rear is closed, of a series of sliding or removable stock-receptacles provided with sample-holding devices at their front ends, substantially as set forth.

3. The combination, with a show-case having a slanting or inclined transparent front and a door behind, by which its otherwise open rear is closed, of a series of sliding or removable stock-receptacles having spaces or compartments at their front ends for holding samples corresponding to the stock behind them, substantially as set forth.

4. The combination, with a show-case having a transparent front provided with a series of numbers or other reference-characters, of a series of removable stock-receptacles provided at their front ends with sample-holding devices and at their rear ends with reference-characters corresponding with those on the said transparent front, substantially as set forth.

In testimony whereof I affix my signature in presence of two witnesses.

WILLIAM P. VROOMAN.
